UNITED STATES PATENT OFFICE

2,359,008

EXHALING VALVE

Oris J. Smith, Cleveland, Ohio, assignor to Air Reduction Company, Incorporated, New York, N. Y., a corporation of New York

Application February 7, 1941, Serial No. 377,787

3 Claims. (Cl. 251—144)

My invention relates to exhaling valves adapted to be used in connection with means including a mask applied to the face of the wearer and providing a closed breathing line, that is, breathing passages wherein, by the use of supplied oxygen and carbon dioxide absorber material, the wearer inhales only from within the system and exhales only a predetermined portion of a given volume of gas inhaled which has means of escape provided by the valve structure.

There are conditions under which such a closed breathing line may have required use wherein it is important to definitely insure that no part of the fluid in which the breather is immersed may by any possibility enter the breathing line through the exhaling valve. Such conditions are found where the apparatus is used under water or in spaces filled with noxious or poisonous gases.

It is therefore a particular object of my invention to provide an exhaling valve, adapted to be used in connection with a closed breathing line, of such a nature that at no time during exhalation—at the moment it begins, while it is taking place or at the moment it ends or after it ends—can there be any introduction into the breathing line of the fluid surrounding the wearer.

To accomplish this object it is a further object of my invention to provide an exhaling orifice having a surrounding valve lip and a grilles or apertured face across the end of the opening in conjunction with a disc of exceedingly thin and pliant material impervious to the passage of fluid such as air and water, whereby upon inhalation at the end of a period of exhalation this pliant and flexible disc will not only seat upon the valve seat but also will seat firmly across the apertured end of the valve opening, thus producing a multiple sealing action. A material suitable for this purpose is composed of woven fabric impregnated with rubber which is known commercially as "lastex" and is about as freely pliable as thin silk fabric.

It is a further object of my invention to support said pliant and flexible disc upon a second disc engaged by a plunger head of solid material such as brass or other metal, which plunger head in turn is engaged by a compression spring of substantially the diameter of the contact edge of the valve seat.

The full objects and advantages of my invention will appear in connection with the detailed description hereinafter given, and the structure

by means of which the advantageous results coming from the practice of my invention are obtained will be particularly pointed out in the claims.

5 In the drawing illustrating an application of my invention in one form,

Fig. 1 is a sectional elevation view of a part of a closed breathing line including a mask applied to the face of the wearer and showing one position for use of my exhaling valve.

Fig. 2 is an end elevation exterior view of the exhaling valve.

Fig. 3 is a sectional elevation view of the exhaling valve and the tubular support for getting it in the closed breathing line taken on line 3—3 of Fig. 2 and presented on an enlarged scale for clear showing of details of construction.

Fig. 4 is a view of the exhaling valve similar to the view of Fig. 2 but taken from the opposite side thereof.

Fig. 5 is a sectional view taken on line 5—5 of Fig. 3.

Fig. 6 is a sectional view taken on line 6—6 of Fig. 4.

25 Fig. 7 is a fragmentary sectional view of parts shown in Fig. 3 with the pliant, flexible disc in the inhalation position.

As shown, a casting 10 is provided with tubular extensions 11 and 12. Extension 11 is adapted to receive a connection 13 from a mask 14 normally to be worn as indicated in Fig. 1. Extension 12 is adapted to receive a tubular member 15 going to any form of apparatus for supplying oxygen and absorbing carbon dioxide in a well-known way. In other words, the casting 10 and extensions 11 and 12 taken together form a part of a passage in a closed breathing line. A second casting 10' is provided with a cylindrical extension 16 which is formed with a multiplicity of apertures 17 and which is externally threaded, as clearly indicated at 18 in Fig. 3. This threaded portion 18 of cylindrical extension 16 is adapted to receive a cylindrical part 19 of a cap 20 which is internally threaded, as indicated at 21 of Fig. 3, and is screwed upon the threads 18 of the cylindrical extension 16, as clearly shown in Fig. 3. Preferably the cylinder 19 is provided with a narrowed ring portion 22 and the cap 20 is provided with a knurled ring portion 23 to facilitate ready turning and locking of the parts. The locking action is effected by means of a spring finger 24 which normally engages the knurled edge of the ring 22, thereby holding the cap 20 and the parts carried thereby in any set position. The cap 20 is provided

with an internally threaded aperture 25, as shown in Fig. 3, into which is threaded a cylindrical boss 28 formed as a part of a cylindrical internal member 27. The member 27, Fig. 3, is provided with an outstanding annular lip 28, the surface 29 of which is brought flush upon the inner surface of the cap 20, as clearly shown in Fig. 3. A nut 30 further clamps the member 27 upon the cap 20. The top of cap 20 is spaced from the end 31 of cylindrical extension 16 so that said cap and the flange 28 may be projected inwardly or outwardly along the cylindrical extension 16 in co-action with the threads 18 and 21.

The casting 10 is provided with an internally threaded cylindrical opening 32 in which is screwed an external cylindrical portion 33 of casting 10', Fig. 3. Casting 10' is also formed with an annular flange member 34, of which the cylindrical member 16 is an extension. An annular valve seat 35 surrounds the end of cylindrical member 33 and is spaced as indicated at 36 in Fig. 3 from a top member 37 which closes the end of the opening 38 extending through the cylindrical extension 33. The top portion 37 is provided with a multiplicity of holes 39 through which the exhalation gases are caused to pass before they go over the edge of annular valve seat 35 and through apertures 17 to the outside of the system.

The member 27 is formed with a central aperture or circular channel 40 in which slides a pin 41 fast on a disc 42 which is circular and extends beyond the limits of the annular valve seat 35. Upon the face of the disc 42 is cemented a rubber disc 43 of the same diameter as disc 42. A strong compression spring 44 surrounds member 27 and engages the disc 42 in a position substantially above the circular edge of valve seat 35, the spring tending to force the discs 42 and 43 toward the valve seat 35 with a pressure which may be varied as desired by rotation of the threaded cap member 19, 20, as will be clearly understood from Figures 2 and 3.

An essential feature of the applicant's invention is the provision of a disc 45 of some extremely flexible and pliable material such as "lastex," which is of substantially the circular area of the area outlined by the inner walls of the member 16. The disc 45 floats freely between the rubber disc 43 and the perforated end wall 37 of passageway 38. This disc is of highly flexible and pliable material and at the same time is impervious to the passage of air. On exhalation it rides against the rubber disc 43 as the force of exhalation pushes the assemblage back against the force of spring 44 to permit the exhaled gases to pass over the circular edge of valve seat 35. Instantly upon stopping of exhalation and beginning of inhalation the spring 44 will cause the disc 45 to engage the circular edge of valve seat 35, and at the same time reduction of pressure within passageway 38 through inhalation will cause the flexible disc 45 to be brought in close contact with the whole surface of the end closure 37, thus sealing the passageway 38 over the holes 39 effectively in addition to the sealing at the circular edge of the valve seat 35.

This valve seat has a sloping wall 46 which is cut into the member 10' as clearly shown at 47 of Fig. 3, leaving an annular raised rim 48 which in effect projects the closure 37 as a sort of protruding table where it will most effectively receive and seat the flexible disc 45.

As a guide for positioning the threaded cap member 19, 20 I provide thereon a distinctive line 50 which may be colored red and which is adapted to cooperate with a pointer 51 held between the castings 10 and 10', Fig. 4. When the pointer and line are in the relative positions of Fig. 4 the apparatus is set for normal operation. As shown in Fig. 2, calibrations may be applied to the drum portion 19 which may carry figures if desired indicating the millimeters of pressure to open the valve. The spring finger 24 may be employed as a pointer indicating relative position of the drum 19 in respect to the calibrations indicated at 52, Fig. 2, and stops 53 and 54 limit the degree of rotation of drum 19.

The advantages of my invention have been in the main pointed out in the preceding description. As stated at the outset the exhaling valve 20 is of particular utility when used under conditions where it is desirable to certainly exclude all the fluid (water or noxious gases) which surrounds the user. Since it is an exhaling valve the valve casing itself must on each exhalation be opened to the space filled with such surrounding fluid. It is the peculiar function and the great advantage coming from the use of my invention that upon reverse operation at termination of exhalation and beginning of inhalation 30 there is an instantaneous and perfect seal effected which will certainly prevent any of the surrounding fluid from finding its way past the valve closure and into the breathing line.

It will be apparent that when such a valve is used—say at considerable depth in the water—the external pressure tending to force the fluid into the breathing line will be relatively great. If the seal were made only at the edge of the valve seat, as is customary with exhaling valves 40 of known types, the small area of the valve closure might not be sufficient to resist this pressure and injection of fluid might take place. My invention, however, provides a secondary seal engaging the relatively large area of the face 45 of the end member covering the holes therethrough, which in conjunction with the seal at the edge of the valve seat, is effective to prevent any ingress of surrounding fluid even where there is great pressure exercised by that fluid.

I claim:

1. An exhaling valve, comprising a casing portion adapted to be inserted in a closed breathing line and having an inlet passageway, said passageway having an end member formed with an external plane surface and a multiplicity of perforations therethrough, a valve seat, a second casing portion surrounding and being spaced from the valve seat, a plunger in the second casing portion having a disc overlying the valve seat, a spring in the second casing portion engaging the plunger disc in an annular line substantially over the edge of the valve seat, and a floating disc of thin pliable material between the plunger disc and the valve seat adapted to seal first against said valve seat and then over said perforations.

2. An exhaling valve adapted for use in a body of fluid to be excluded from the inside of the valve, comprising a casing portion adapted to be inserted in a closed breathing line and having an inlet passageway adapted to be immersed in said fluid, an end of said casing portion protruding from said passageway and formed with a perforated partition across said passage 75 with an exposed outer plane face, an edged an-

nular valve seat formed on said casing portion and being spaced from the outer annular wall of said end portion and having its edge in a plane outside of the plane of said face, a plunger in the casing having a circular head, and a floating disc of thin pliable material between the plunger head and valve seat, whereby the valve disc will be first moved away from said plate and then moved with the plunger head away from the edge of said valve seat to permit escape of gases and prevent ingress of fluid into the valve inlet passageway.

3. An exhaling valve adapted for use in a body of fluid to be excluded from the inside of the valve, comprising a casing portion adapted to be inserted in a closed breathing line and having

an inlet passageway adapted to be immersed in said fluid, an end of said casing portion protruding from said passageway and formed with a perforated partition across said passage with 5 an exposed outer plane face, an edged annular valve seat formed on said casing portion and being spaced from the outer annular wall of said end and having its edge in a plane outside of the plane of said face, a plunger in the casing 10 having a circular head, a floating disc of thin pliable material between the plunger head and valve seat, and a helical spring engaging the plunger head in a circle directly above the annular seat edge.
